DESIGN FOR A SERVING TRAY OR SIMILAR ARTICLE

Inez C. Crimmins, Minneapolis, Minn.

Application November 6, 1946, Serial No. 134,545

Term of patent 14 years

(Cl. D44—10—(14))

To all whom it may concern:

Be it known that I, Inez C. Crimmins, a citizen of the United States, residing at Minneapolis, in the county of Hennepin and State of Minnesota, have invented a new, original, and ornamental Design for a Serving Tray or Similar Article, of which the following is a specification, reference being had to the accompanying drawings, forming part thereof.

Fig. 1 is a perspective view of a serving tray or similar article showing my new design;

Fig. 2 is an edge elevational view; and

Fig. 3 is a plan view thereof.

I claim:

The ornamental design for a serving tray or similar article, as shown.

INEZ C. CRIMMINS,
